(57) CLAIM

The ornamental design for a cigar holder for golf cart, as shown and described.

DESCRIPTION

FIG. 1 is a perspective exploded view of a cigar holder for golf cart showing my new design;

FIG. 2 is a left side view thereof;

FIG. 3 is a top view thereof;

FIG. 4 is a right side view thereof;

FIG. 5 is a bottom view thereof;

FIG. 6 is a front view thereof; and,

FIG. 7 is a back view thereof.

The broken line showing in FIG. 1 of the cigar, including its textured tip, are included for the purpose of illustrating environment of the design and forms no part of the claimed design.

1 Claim, 2 Drawing Sheets

FIG. 3

FIG. 4

FIG. 5

FIG. 6

FIG. 7
